UNITED STATES PATENT OFFICE.

JOHN XAVIER, OF CLEVELAND, OHIO, ASSIGNOR TO AMERICAN CAN COMPANY, OF NEW YORK, N. Y., A CORPORATION OF NEW JERSEY.

SHEET-METAL DISPLAY-CAN.

No. 922,831.

Specification of Letters Patent.

Patented May 25, 1909.

Application filed November 6, 1907. Serial No. 400,998.

To all whom it may concern:

Be it known that I, JOHN XAVIER, a citizen of the United States, residing in Cleveland, in the county of Cuyahoga and State of Ohio, have invented a new and useful Improvement in Sheet-Metal Display-Cans, of which the following is a specification.

My invention relates to sheet metal display cans.

10 The object of my invention is to provide a sheet metal display can having the customary sheet brass front plate furnished with a display opening at its lower part closed by a removable glass plate and which will have simple and efficient and conveniently applicable or removable means for preventing the crackers or other bakery goods contained in the can from coming in direct contact with the upper portion of the brass front plate above the display opening.

15 My invention consists in the novel construction of parts and devices and in the novel combinations of parts and devices herein shown and described and by which this object or result is practically accomplished.

20 In the accompanying drawing forming a part of this specification, Figure 1 is a perspective view of a sheet metal display can embodying my invention. Fig. 2 is an enlarged central vertical section on line 2—2 of Fig. 1. Fig. 3 is a vertical section on line 3—3 of Fig. 2, certain parts appearing in elevation partly broken away. Fig. 4 is a detail perspective view of the removable holder for the paper sheet or board which protects the crackers or bakery goods from coming in contact with the upper portion 25 of the brass front plate of the can. Fig. 5 is a detail perspective view of the removable protecting sheet of paper, paper-board or other material and, Fig. 6 is a detail plan view showing one corner of the can body, the 30 cover being open or removed.

In the drawing, A represents the bottom plate of the can, B, B, B the upright side plates of the can body, D the brass front plate of the can body, C the removable glass plate and K the hinged cover.

The upright side plates B and front plate D are united together at the upright corners of the can by internally folded lock seams b and to the bottom plate A by externally 55 folded lock seams a. The upright side plates

B of the can body are furnished at their upper ends with integral hollow triangular strengthening bars B² formed by integral horizontal flanges b¹ and angle flanges b², the horizontal flanges overlapping each other 60 at the corners, and soldered or otherwise secured together as indicated at b³ in Fig. 6. And the upper end of the can body at the front adjacent to the front plate D is furnished with a similar hollow triangular 65 strengthening brace B³, the horizontal flange or member b⁴ of which is secured by a lock or folded seam b⁵ to the flange d at the upper marginal edge of the front plate D, and the inclined flange b⁶ of which has a slot or 70 opening b⁷ between its lower edge b⁸ and the adjacent wall of the front plate D for reception of the angle flange n of the removable holder N of the paper or paper-board protecting sheet P.

75 The sheet brass front plate D of the can is provided at its lower half or portion with a display opening D¹ therein, preferably surrounded by a marginal bevel or angle flange d¹ provided with a fold d² at its extreme edge to further stiffen and strengthen the front plate and give a smooth finish to the display opening therein.

The brass front or display plate D of the can is provided at its upper half or part with 85 a sunken, recessed or depressed portion D² surrounded by a marginal bevel or counter-sink-wall d³, this recess or sunken portion serving to strengthen and stiffen the thin sheet brass front plate of the can and also 90 to form a seat to receive a paper sign or label M, preferably pasted thereon, the depression serving to protect the paper label from being scratched or injured in shipment or handling of the cans.

95 The removable glass plate C is held removably in place on the inside of the can so as to snugly close the display opening in the front plate at its lower edge by means of a fixed guide or holder G of sheet metal, having an upwardly projecting lip g furnished with a folded edge g¹ and with a seaming flange g² which is interfolded with the lock seam a at the front lower corner of the can, and which seam unites the lower edge of the 100 front plate D with the front edge of the bottom plate A. And the glass plate is so removably held in place at its upper edge by a fixed guide or bridge H of sheet metal extending across and soldered or otherwise 105

secured to the front plate D above the display opening D¹ therein and soldered or otherwise secured at its ends to the adjacent upright side plates B B of the can body.

5 This front-plate bracing and supporting and glass-plate holding bridge or fixed guide H is of an angle form in cross section having a horizontal flange or member h reinforced by a fold h¹ and a depending or vertical member h² furnished with a marginal fold h³ at its lower edge, the depending or vertical member h² being adapted to overlap or overhang the upper edge of the glass plate C when the glass plate is in position and resting with its lower edge on the bottom plate of the can.

10 To remove the glass plate C, it is first slipped upward until its lower edge will clear the upper edge of the upturned lip g of the lower holder G and then by tilting the glass plate inward at its lower part, its upper edge can be freed from the upper fixed guide or folder H. To lock the glass plate from slipping upward, its upper fixed guide or holder H is furnished with a spring catch or keeper H¹, secured thereto preferably by a rivet h⁴, and which engages the upper edge of the glass plate C to hold it from slipping or being slipped upward except when the spring catch H¹ is first compressed.

15 The protecting sheet P is preferably of paper, paper-board, card-board or other suitable material other than brass and covers on the inside the upper portion of the brass front plate and prevents the crackers or other contents of the can from coming in direct contact with the brass front plate. This protecting sheet P, when made of paper or other cheap material, may be renewed from time to time at slight cost. It is removable supported on the interior of the can adjacent to the upper portion of the brass front plate by means of a removable protecting-sheet holder N, preferably of tin plate and provided at its lower end with an inturned flange or hook n¹ to engage and support the lower edge of the protecting sheet P, and it is provided at its upper end with an inturned flange or hook n² adapted to hook over and engage the upper edge of the protecting sheet P. The protecting sheet holder N is further provided at its upper end with a reversely inclined flange or lip n, which with the flange n² forms an upwardly projecting hook to receive the lower inclined flange or member b⁶ of the angular strengthening bar B³ at the upper end of the brass front plate B of the can. The removable projecting sheet holder N is inserted in the slot b⁷ by turning the holder N at an angle so that its flange or lip n will enter the slot b⁷, and then after the supporting flange n is inserted, turning the holder N down into an upright position as shown in Fig. 2 of the drawing. The holder N with the protecting sheet therein is thus rigidly and firmly sus-

pended or supported from the angular strengthening bar at the upper end of the can body adjacent to the brass front plate thereof while at the same time the protecting sheet may be conveniently and easily removed when desired for cleaning the interior of the can or for renewing the protecting sheet P.

The hinged cover K is or may be of any usual or customary construction. Its flange K¹ is preferably integral at three sides, but at the front of the can the flange is preferably of brass K². The cover preferably has a marginal stiffening wire K³ at the lower edge of its depending flanges, this wire also serving at the back of the can as the pintle of the hinge.

It will be observed that in my improved can the whole interior face of the brass front plate is covered by sheets of other material than brass, so that the crackers cannot come in direct contact with the brass front plate and be injured thereby. The crackers are protected from coming in contact with the lower portion of the brass front plate by the removable glass plate and from coming in contact with the upper portion of the brass front plate by the protecting plate P and from coming in contact with the narrow intermediate portion of the brass front plate by the angular guide or holder H which extends entirely across the brass front plate at its middle portion, and which holds the upper edge of the glass front plate in place. The crackers are prevented from coming in contact with the brass front plate of the can at the extreme top portion thereof by the angular strengthening bar B³ which is of tin plate.

I claim:

1. In a sheet metal display can, the combination with the brass front display plate, of an angular strengthening bar at the upper edge of the front plate having a depending angle flange or member, and a removable protecting sheet holder having an angle flange engaging said angle flange of said angular strengthening bar, provided at its lower edge with an upturned hook to receive and support a protecting sheet, substantially as specified.

2. In a sheet metal display can, the combination with the brass front display plate, of an angular strengthening bar at the upper edge of the front plate, having a depending angle flange or member, and a removable protecting sheet holder having an angle flange engaging said angle flange of said angular strengthening bar provided at its lower edge with an upturned hook to receive and support a protecting sheet and a protecting sheet in said holder, substantially as specified.

3. In a sheet metal display can, the combination with the brass front display plate

having a display opening therein at its lower part, a removable glass plate for closing the opening in said brass front plate and for protecting the crackers from contact with the 5 lower portion thereof, an angle bar guide or holder extending across the middle portion of the brass front plate to hold the upper edge of the glass plate in place and to protect the crackers from contact with the middle 10 portion of the brass front plate, a strengthening bar at the upper edge of the brass front plate to strengthen the can and protect the crackers from contact with the extreme upper portion of the brass front plate, a protecting sheet holder engaging and suspended 15 from said strengthening bar, provided with an upturned hook at its lower end to receive and support a protecting sheet and a removable protecting sheet in said holder to protect the crackers from contact with the upper portion of the brass front plate, substantially as specified.

4. In a sheet metal display can, the combination with a brass front plate having a 25 display opening therein at its lower part, of a strengthening bar at the upper edge of said brass front plate, and a protecting sheet holder, provided with an upturned hook at its lower end to receive and support a protecting sheet said strengthening bar and said 30 protecting sheet holder having interengaging means for suspending the holder from the strengthening bar, substantially as specified.

5. In a sheet metal display can, the combination with a brass front plate having a 35 display opening therein at its lower part, of a strengthening bar at the upper edge of said brass front plate, and a removable protecting sheet holder, provided with an upturned 40 hook at its lower end to receive and support a protecting sheet said strengthening bar and said protecting sheet holder having interengaging means for suspending the holder from the strengthening bar, substantially as specified.

from the strengthening bar, substantially as specified.

6. In a sheet metal display can, the combination with a brass front plate having a 45 display opening therein at its lower part, of a strengthening bar at the upper edge of said brass front plate, and a protecting sheet holder, provided with an upturned hook at its lower end to receive and support a protecting sheet, said strengthening bar and said 50 protecting sheet holder having interengaging means for suspending the holder from the 55 strengthening bar and a protecting sheet in said holder, substantially as specified.

7. In a sheet metal display can, the combination with a brass front plate having a display opening therein at its lower part, of a 60 strengthening bar at the upper edge of said brass front plate, and a removable protecting sheet holder, provided with an upturned hook at its lower end to receive and support a protecting sheet said strengthening bar and a 65 protecting sheet holder having interengaging means for suspending the holder from the strengthening bar and a protecting sheet in said holder, substantially as specified.

8. In a sheet metal display can, the combination with a brass front display plate and a strengthening bar at the upper edge thereof having a depending angle flange with a slot between the same and said brass plate, of a removable protecting sheet and a removable 75 holder therefor having oppositely projecting hook flanges at its upper and lower edges for engaging the protecting sheet and an angle flange at its upper edge for engaging the angle flange of the strengthening bar, substantially as specified.

JOHN XAVIER.
